UNITED STATES PATENT OFFICE.

HENRY ERICSSON, OF CHICAGO, ILLINOIS.

SCAFFOLD.

Application filed December 29, 1922. Serial No. 609,569.

My invention has reference more particularly to a portable support for construction or repair work whereby the workmen may be optionally positioned at desired elevations for conveniently accomplishing the work.

In construction and repair jobs, a large part of the work is required to be performed on scaffolds or supports, the elevation of which in many cases must be changed from time to time as the work progresses, so that the men are conveniently positioned to perform the work. The erecting of scaffolds such as are ordinarily used, tearing them down and rebuilding them at different elevations usually requires considerable time and attention and involves considerable loss, which may be avoided if a scaffolding is provided which is adjustable to various elevations and suitable for practically every character and all conditions of construction and repair work, and which may be easily and quickly assembled and taken apart and transported from place to place, and which affords the greatest convenience to the workmen for accomplishing or performing the work.

The principal objects of my invention are to provide a scaffold which may be conveniently adjusted to various elevations; to construct the scaffold in a knock-down form so that it may be readily taken apart and assembled; to design the parts into which the scaffold is separable so that they may be easily carried by the workmen from place to place; to provide a runway in connection with the scaffold whereby materials for the workmen are conveniently brought to them; and, in general, to provide an improved portable and adjustable scaffold which is simple and inexpensive and very substantial, so as to be perfectly safe to work upon, and arranged to facilitate the performance of the work and thereby increase the efficiency of the workmen.

On the drawings:

Fig. 1 is an end view of a scaffold embodying my improvements with portions broken away to disclose details of the construction;

Fig. 2 a sectional view on the line 2—2 of Fig. 1; and

Fig. 3 a side view of the scaffold with intermediate portions broken away and taken on the line 3—3 of Fig. 1.

This scaffold is composed of a pair of standards which are spaced apart a suitable

distance and have platforms thereon for supporting the workmen and materials. Each of these standards is composed of a base 1, consisting of a pair of elongated plates 2 and 3, which are secured together at right angles and one above the other, the upper plate being provided at the outer ends with blocks 4 on the under side having their under surfaces lying in the same plane as the under surface of the plate 3. A flanged fitting 5 is secured to plates 2 and 3 at their intersection by means of cap screws or bolts 6, which also serve to connect the plates together, and this fitting has a reduced stem 7 preferably threaded into the fitting 5 and projecting upwardly therefrom. A pipe 8 telescopes onto the stem 7 and at the upper end thereof is provided with a flanged cap 9, and this cap 9 supports a bracket 10, in which the sheave 11 is journaled. The bracket 10 has a base in the form of a flange corresponding to the flange of the cap 9 and is secured to the latter by a pivot pin 12 which permits the bracket 10 to swing around on the upper face of the cap 9. The cap 9 is connected to the pipe 8 in any suitable manner; but preferably by means of a threaded connection, so that it may be readily detached from the pipe 8 for separating the scaffold into suitable parts which may be readily carried by the workmen from place to place.

The base of the standard may be reinforced if desired, by one or more truss-rods 13 which extend under the plate 3 and have the ends connected respectively to the ends of the plate 2 or near the ends thereof inwardly of the blocks 4, and the connection of the pipe 8 with the base may also be reinforced by a number of detachable braces 14, which may be removed when the scaffold is lowered and installed as the scaffold is elevated. These braces have hooks 15 at the upper ends which engage in apertures 16 provided in the pipe 8 at an elevation above the lower end, and the outer ends are adapted to be secured by bolts 17 or other suitable connecting means to the outer ends of the plates 2 and 3, so that when the hooks 15 are engaged in the apertures 16 and the fasteners 17 applied, the braces 14 are held securely in place and afford a substantial lateral reinforcement for the pipe 8.

Mounted on each standard is a platform supporting frame consisting of a pair of members 18 which are spaced apart a dis-

2

tance substantially equal to the diameter of the pipe 8, so that the latter may be inserted therebetween, and at an elevation above the members 18 is another pair of shorter but 5 similar members 19, which are likewise spaced, and the members 18 and 19 are connected together and each pair mounted in the required spaced relation by members 20, 10 and 22, the latter of which project some- 15 what above the members 19 and are suitably spaced to engage against the opposite sides of the pipe 8 and serve as guides to permit sliding movement of the frame along the pipe 8. The members 18 project at one side 20 beyond the members 19 and carry a platform for supporting the workmen, said platform consisting of one or more boards 23, which have cleats 24 extending across the under side adjacent each end to engage between the 25 strips 18 of the sliding frames of two spaced standards for holding the boards 23 against displacement. The outer ends of the members 18 are connected by an end cleat 25 which serves to hold said members in proper spaced relation and engages the ends of the cleats 24 so as to prevent displacement of the boards 23 endwise from the members 18.

A platform is also provided on the members 19 for supporting the materials used by 30 the workmen, as for example, the bricks and mortar in masonry construction, said platform consisting of a number of boards 26 and 27, which are likewise provided with cleats 28 to engage between the members 19 for holding the boards in place. The board 27 is cut away as indicated at 29, or otherwise constructed to straddle the posts 8 and guides 22 at the ends.

A hanger 30 is secured to one of the guides 40 22 of each sliding frame, and has a cable 31 connected thereto and passed over the sheave 11, and the other end of this cable is connected to a drum 32 of a windlass which is journaled in a bracket 33 mounted on the 45 other guide 22. This drum has a ratchet wheel 34 at one end operable by a pawl 35 on a swinging arm 36 which is pivoted on the shaft 37 which carries the drum 32, and the outer end of the arm 36 is formed with a 50 socket to receive the bar or pipe 38 which affords sufficient leverage to operate the windlass. A holding pawl 39 is pivoted on the bracket 33 to engage the teeth of the ratchet wheel 34 to lock the drum in various 55 positions to which it may be adjusted.

A large part of the work which is required to be done on scaffolds necessitates the furnishing of materials to the workmen on the scaffold from time to time, and in order that 60 this may be conveniently done without interfering with the workmen, I have constructed my scaffold so that a runway or platform may be mounted at the opposite side of the scaffold from the platform 23 65 on which the workmen stand. To this end

there are extensions 40 which are detachably secured by bolts 41 or other suitable fastenings between the ends of the members 18 for supporting boards 42 composing the runway or platform. The outer ends of the extensions 40 are each provided with a U-shaped strap 43 through which a 2 x 4 or other suitable supporting post 44 may be inserted and a cam 45 is pivoted between the two arms of the strap 43 so that when it is 70 rotated to the position shown by full lines in Fig. 1, it serves to clamp the post against the outer end of the strap 43, the said outer end being preferably formed as shown in Fig. 1, with edges which bite into the outer 75 edge of the post 44 and insure a substantial connection of the extensions 40 with the post.

In using this scaffold the standards are first set up adjacent the place where the work is to be performed and the sliding 80 frames mounted on the standards and the platforms 26-27 and 23 assembled thereon with the latter arranged close to the location where the work is to be performed. The braces 14 however, are not installed and thus 85 permit the sliding platform to be arranged as shown by dotted lines in Fig. 1, very close to the floor on which the standards are mounted, a pair of cleats 46 being preferably 90 provided at the ends of the strip 2 and corresponding in thickness to the flange of the fitting 5 to afford a rest for the sliding members in the lowermost position.

As the work progresses the windlass is operated to wind up the cable 31 and thereby 100 raises the sliding frames and the platforms thereon, so that the workmen may be positioned at all times at the elevation most convenient for performing the work. After the scaffolds have been elevated to a point 105 above the openings 16, the brace rods 14 are then applied to reinforce the standards against lateral strain due to weight of the workmen and materials on the elevated scaffold. As the work begins, the platform 110 26-27 for the materials is sufficiently close to the floor so that the materials may be readily brought up and placed on said platform from the floor, but as the scaffold is elevated, it is desirable to have an elevated 115 platform for bringing up materials to the workmen. Therefore, after the scaffold has been elevated somewhat the extensions 40 are mounted in place with the outer ends connected with supports 44 and the platform 42 assembled on the extensions 40 and an inclined runway may be constructed up to the platform 42 so that materials may be readily wheeled up on to the platform 42 and deposited on the platform 26-27. 120 Therefore, whenever the scaffold is elevated, the cam member 45 is first swung to the position shown by dotted lines in Fig. 1 to release the extensions 40 from the post 44 and as the scaffold is elevated the extensions 40 13

and platform 42 are likewise elevated, and when the proper elevation is reached, the cam member 45 is returned to the position shown by full lines in Fig. 1, to clamp the outer end of the extensions 40 to the supporting post 44.

The elevated platform 26-27 is desirable in most construction work to support the materials at an elevation convenient for the workman so that he does not have to stoop over to take up the materials to be used in the work, but this platform 26-27 may of course, be dispensed with if desired and merely a single platform provided.

While I have shown and described my invention in a preferred form, I am aware that various changes and modifications may be made without departing from the principles of my invention, the scope of which is to be determined by the appended claims.

I claim as my invention:

1. In a portable scaffold, a plurality of standards each having a single upright, a pair of frame members on opposite sides of and extending horizontally at right angles to the uprights, a platform extending between and detachably connected with the members on each upright, spaced vertical parallel guides on diametrically opposite sides of said uprights parallel thereto and connected to said frame members, a base having an upright pin for receiving each upright thereover, said uprights being of tubular formation of uniform diameter to permit the platform and frame members to be lowered to the base.

2. In a portable scaffold, a plurality of standards each having a single upright, a pair of frame members on opposite sides of and extending horizontally at right angles to the uprights, a platform extending between and detachably connected with the

members on each upright, spaced vertical parallel guides on diametrically opposite sides of said uprights parallel thereto and connected to said frame members, a base on which each upright is mounted, a windlass on each pair of guides, a sheave mounted on the upper end of each upright, and a cable connected to each windlass and extending over a sheave with the opposite end of each cable anchored to cause raising or lowering of the frame members and platforms when the windlass is actuated.

3. In a portable scaffold, a plurality of standards each having a single upright, a pair of frame members on opposite sides of and extending horizontally at right angles to the uprights, a platform extending between and detachably connected with the members on each upright, spaced vertical parallel guides on diametrically opposite sides of said uprights parallel thereto and connected to said frame members, a base on which each upright is mounted, a windlass on each pair of guides, a sheave mounted on the upper end of each upright, cables connected to the windlasses and trained over the sheaves, the opposite ends of the cables being connected to the guides on the opposite sides of the uprights to cause raising and lowering of the frames and platforms when the windlasses are operated, a second platform disposed laterally from and movable vertically with the first platform, upright posts for supporting the outer extremity of the second platform, and detachable clamping connections carried by the outer end of the second platform and movable over the posts or operative to clamp the posts and support the outer ends of the second platform.

HENRY ERICSSON.
